Primary Examiner — Leanne Was-Englehart*Assistant Examiner* — Alison Davis*(74) Attorney, Agent, or Firm* — Addison D. Ault; IP Gentleman Intellectual Property Services, LLC(57) **CLAIM**

The ornamental design for a monitor, as shown and described.

DESCRIPTION

FIG. 1. is a perspective view of a monitor showing the design;

FIG. 2. is a second perspective view thereof;

FIG. 3. is a front elevation view thereof;

FIG. 4. is a rear elevation view thereof;

FIG. 5. is a left side elevation view thereof;

FIG. 6. is a right side elevation view thereof;

FIG. 7. is a top plan view thereof;

FIG. 8. is a bottom plan view thereof;

FIG. 9. is a perspective view of the monitor in a partially folded position; and,

FIG. 10. is a perspective view of the monitor in a folded position.

The broken lines show portions of the article that form no part of the claimed design.

1 Claim, 10 Drawing Sheets(56)
